UNITED STATES PATENT OFFICE.

EDWARD P. COLE, OF CHICAGO, ILLINOIS.

COAL AND GAS RANGE.

1,344,755.

Specification of Letters Patent. Patented June 29, 1920.

Application filed March 27, 1917. Serial No. 157,610.

To all whom it may concern:

Be it known that I, EDWARD P. COLE, a citizen of the United States, residing at Chicago, in the county of Cook and State 5 of Illinois, have invented certain new and useful Improvements in Coal and Gas Ranges, of which the following is a specification.

My invention relates to combination gas 10 and coal ranges which are adapted to use either coal or gas as a fuel, and more particularly relates to the gas burning system for heating the oven of such a range. Various combinations of this general character are 15 known, many of which include a removable burner pipe and burner secured to and associated with a deflecting plate arranged to be inserted in the lower part of the oven, this making a heavy and unwieldy structure which it is difficult for a housekeeper 20 to handle. In other combinations a gas burner is permanently arranged in a circular opening at the bottom of the oven, but commonly the burner used is one variety 25 or another of the ordinary star or circular types having a punctured or slotted burner member which burns the gas in jets, and which necessitate a relatively large opening and the admission of a relatively large volume 30 of cold air to secure proper combustion, which very materially diminishes the heating effect of the flame and reduces the efficiency of the burner. By the use of a Bunsen burner in my improved stove, as 35 hereinafter described, the entrance and circulation of this large excess of air through the oven is prevented, and the oven rendered quicker to heat, more economical in consumption of gas and more efficient generally. 40 A further feature of my invention is the circulation of burnt gases downwardly through a space between the back wall of the oven and the flue, giving a greater heating effect and preventing the too hasty escape of the exhaust gases in the flue. 45 This circulation is permitted through the automatic opening of a door or gate in a wall between the space mentioned and the flue, as hereinafter described. Other features 50 of my invention consist in the arrangement and construction of parts whereby I attain various advantages which will be apparent from the description hereinafter given, and which contribute to the production and embodiment of a useful and desirable combination range of the general

character above mentioned, the essential elements of my invention being more particularly pointed out in the appended claims.

In the drawings, Figure 1 is a central 60 vertical section from side to side of a combination range embodying my invention; Fig. 2 is a horizontal section on the line 2—2 of Fig. 1; Fig. 3 is a similar section on the line 3—3 of Fig. 1; and Fig. 4 is a 65 cross section, or section from front to rear, on the line 4—4 of Fig. 2.

The same reference characters indicate the same parts in all the figures of the drawing.

To afford a basis for explanation of the parts to which the present invention particularly relates, a brief description of the general construction of the combined range will first be given. It will be understood that 70 the stove is constructed of various cast and sheet metal parts making up the framework, walls, doors, etc., secured together, or hinged, as the case may be, by bolts, screws, rivets, or other suitable means, and that the 75 particular form and number of parts is immaterial, except so far as they contribute to forming a structure exhibiting the relation of walls, passages, chambers, etc., now to be described.

The fire-box section of the stove is divided into a fire-box 1, supplied through a suitable covered feed chute 2, and an ashpit 3 separated by a suitable rocking grate 4 from the fire-box, doors being provided for 90 access to the fire-box and ash pit, and a suitable damper being provided to govern the draft. At the side of the fire-box section, the oven 5 is arranged, the top wall 6 of the oven being below the top plate 7 of 95 the stove frame structure, thus leaving a space between the two constituting a part of the flue passage. The wall 8 of the oven opposite the fire-box is likewise spaced inwardly from the adjacent outer wall 9 of 100 the stove, and the bottom wall 10 of the oven is supported above the outer base wall 11 of the stove, the space between the oven walls and the outer frame and casing walls being continuous and forming parts of the 105 flue passages. In practice the top and both sides of the oven may conveniently be formed of a single sheet of metal bent on transverse lines and lying between the front outer wall of the stove and the rear wall 110 thereof, the forward oven walls being formed with marginal flanges by means of

which they are riveted to the front and rear walls of the stove, and the bottom of the oven may be formed of a metal sheet riveted to the side oven walls and to the front and rear walls of the stove structure. 5 Below the oven the flue space is divided by a diagonal partition 12 extending from below the rear end of the wall 8 to a cylindrical partition 13 which surrounds an opening extending through the bottom or base wall of the stove and opening into the oven. 10 The partition 12, with the cylindrical partition 13, together form a continuous barrier causing a deflection of the products of combustion around the cylindrical partition. 15 At the rear of the stove and below the side of the oven adjacent the fire-box section, the space between the oven and bottom wall of the stove communicates through a large 20 opening with the bottom of the back smoke flue section 15. This smoke flue section is a vertical rectangular pipe or casing, the front wall of which is contiguous with the rear wall of the stove casing structure, except for the opening at the bottom, and which at the top is formed with the usual 25 pipe collar. The products of combustion, it will be observed, following the path of the arrows, pass from the fire-box 1, over 30 the top of the oven, down the side opposite the firebox, under the bottom, and enter the smoke flue at one side of the rear of the oven. All the parts thus far described, it will be understood, excepting that the opening 35 13 is relatively small in size as compared with previous structures, are old in the art.

Describing now the parts to which my invention more particularly relates, the sides of the oven near the bottom thereof are 40 equipped with guides 17 for the reception of a removable wire rack 18, to the under side of which is attached a shield 19 consisting of opposite sheet metal facings and an interposed layer of asbestos, secured together, and below the shield a hollow cast-iron flame-spreader or deflecting plate 20 of 45 widely flaring bell-shape, as illustrated. The rack, shield and spreading plate are bolted or otherwise secured together, so that 50 they can be removed as a whole. The axis of the deflecting plate is coaxial with the opening of the partition 13, and its lower end is arranged about on a level with the top of such opening, in proper position to 55 act most efficiently as a spreader for a gas flame below it in the opening. This deflecting plate, or flame-spreader, is directly acted upon by the flame, but owing to its spreading hollow form the heat imparted to it is 60 to some extent conveyed by conduction outwardly to and along its line of contact with the shield, so that the heat is quite evenly distributed. The distribution of heat is further 65 equalized by the conductive action of the sheet metal facings of the shield, on

opposite sides of the asbestos lining, the facings serving to distribute the heat laterally, and the lining serving to baffle, to some extent, a direct upward movement of the heat rays, so that a very uniform distribution of heat to the oven is attained. 70

The single port Bunsen burner 21 which I employ is arranged centrally in the opening 13 at the end of the burner pipe 22, which pipe is connected with the gas supply 75 pipe 23 through a mixing valve 24 by means of which a mixture of gas and air is supplied to the burner. A suitable and effective valve for the purpose is the valve known commercially as the "Hale gas mixer," constructed under United States Patent No. 970,919, which operates to properly proportion the amount of air with respect to the gas in the mixture as the valve is turned on or off. The burner tube is preferably 80 formed with an internal bead or constriction near the outlet, and adjacent the outlet the inner wall of the tube is beveled or cut away, the formation of the parts in this manner acting to increase the velocity of the 85 stream of mixture at the burning point, in the manner of a Venturi tube. This arrangement produces a single jet blue flame of the highest possible temperature, which is spread by the deflecting plate 20 in a solid 90 sheet of flame practically filling the entrance into the oven in such manner as to distribute the heat evenly through and around the shield and produce a proper baking effect with a minimum consumption of gas. Since 95 100 all the air needed for combustion is supplied by the mixing valve, the opening 13 need be relatively small and practically no air is heated and carried uncombined past the flame into and through the oven. 105

In order to enable the gas to be lighted by hand, an opening is formed through the circular deflector and asbestos shield which may be opened and closed by a sliding plate 26 or other suitable closure, to give access to 110 the burner and permit a match to be applied. I have further provided, however, a convenient lighter of well-known construction, consisting of a tube 35 which at the end adjacent the burner is formed with a jet orifice 36 approximately in alignment with the burner orifice and a short distance below the same. A push-button valve 37 is provided which is constructed to permit the continuous passage of a minute flow of gas 115 at the jet orifice, which is kept constantly lighted, thus maintaining a very small flame. Depression of the push-button operates to admit full pressure, thus causing the flame to jet into the path of the burner orifice and light the gas mixture issuing therefrom. 120

It will be understood that when the range is burning coal, the rack 18 with its associated parts, the asbestos shield and spreading 125 130

plate, are removed; and that these parts are replaced in the oven when gas is to be used as fuel. A small lid adapted to rest in a seat at the top of the opening 13 is provided, 5 which lid is removed when gas is to be used, and is placed in position to cover the opening when the range is being used with coal.

The rear wall of the oven is formed by a 10 sheet of metal 27 which is spaced inwardly a short distance from the rear outer wall of the stove structure, thus providing a space 28 between the oven and the back stove wall and back smoke flue, which latter, as before 15 stated, is contiguous with a part of such stove wall. The top of this rear oven wall is provided with a number of large openings 29 providing free communication between the oven and the space back thereof, 20 and at the lower end of the space 28 and opposite the back flue an opening 30 is provided, large enough to afford free communication with such flue. This opening is opened and closed by a cover 31 which stands 25 normally closed when coal is being used and the rack 18 is removed, but which is automatically opened by the insertion of such rack preparatory to burning gas. To this end the door 31, pivoted in a frame 32 secured 30 in an opening in the wall between the back of the stove structure and the smoke flue, is weighted so that it will normally seat in the frame and close the opening. The door is provided with a downwardly 35 extending finger or lever 33 lying in the path of a projection consisting of a loop 34 extending rearwardly from the rack 18, which loop, when the rack 18 is pushed rearwardly to its normal position in the guides 40 17 will extend through a slot in the rear oven wall 27 and contact the finger 33 so as to open the door and maintain it open so long as the rack is in place. This arrangement of a downward draft at the back wall 45 holds the heat in the oven, utilizes to the greatest extent the heat in the gases, and prevents their too speedy escapement into the flue.

It will be understood that various changes 50 may be made in the design and construction of the parts of my invention without departing from the spirit thereof, and my claims are therefore not limited to the specific form and design of elements above described.

I claim:

1. In a combined coal and gas range having an oven and a flue passage between the bottom of the oven and the outer bottom 55 wall of the stove and a circular partition extending from said stove bottom to said oven bottom and forming a circular opening

into oven and a single port burner arranged within said opening, means for distributing the heat of the burner comprising a flaring 65 heat-conductive metal flame-spreader having its apex extending into said opening adjacent said burner and a laminated shield having highly conductive and relatively non-conductive layers in contact with said flame-spreader. 70

2. A range according to claim 1 in which said shield consists of a layer of asbestos interposed between metal sheets.

3. In a combined coal and gas range having an oven and a smoke-flue and formed with an intermediate chamber adjacent and coextensive with the vertical rear wall of the oven and arranged intermediate such wall and the flue, said oven wall communicating at its top with said intermediate chamber, a door adjacent the bottom of said intermediate space governing communication between such space and the smoke-flue, a gas burner arranged to discharge its products of combustion into the bottom of the oven, and a rack insertible into said oven and arranged to open and close said door. 75 80 85

4. In a combined coal and gas range having an oven and a smoke-flue and formed with an intermediate chamber adjacent and coextensive with the vertical rear wall of the oven and arranged intermediate such wall and the flue, said oven wall communicating at its top with said intermediate 90 chamber, a door adjacent the bottom of said intermediate space governing communication between such space and the smoke-flue, a gas burner arranged to discharge its products of combustion through an opening into 95 the bottom of the oven, a sliding rack equipped with a flame-spreader arranged to be inserted in guides adjacent the bottom of the oven, said door being arranged to be opened and closed by said rack. 100 105

5. In a combined coal and gas range having an oven and a smoke-flue and formed with an intermediate chamber adjacent and coextensive with the vertical rear wall of the oven and arranged intermediate such 110 wall and the flue, said oven wall communicating at its top with said intermediate chamber, a door normally held closed by gravity adjacent the bottom of said intermediate space and governing communication 115 between such space and the smoke-flue, said door being equipped with an opening lever, a gas burner arranged to discharge its products of combustion into the bottom of the oven, and a sliding rack insertible into said 120 oven and having a member adapted to contact said opening lever on the door.

EDWARD P. COLE.
